Primary Examiner — Ricky Pham(74) *Attorney, Agent, or Firm* — Hanley, Flight & Zimmerman, LLC(57) **CLAIM**

The ornamental design for a “lid for cooking pot”, as shown and described in FIGS. 1-7.

DESCRIPTION

FIG. 1 is a perspective view of a lid for a cooking pot.

FIG. 2 is a front view of the lid of FIG. 1.

FIG. 3 is a rear view of the lid of FIG. 1.

FIG. 4 is a right side view of the lid of FIG. 1.

FIG. 5 is a left side view of the lid of FIG. 1.

FIG. 6 is a top view of the lid of FIG. 1; and,

FIG. 7 is a bottom view of the lid of FIG. 1.

The features shown in broken lines form no part of the claimed design.

The lighter solid lines denote surfaces and contours. Line shading is not surface ornamentation.
